UNITED STATES PATENT OFFICE.

LOUIS JACOT, OF BIRMINGHAM, ENGLAND.

DESIGN FOR A WRISTLET-WATCH COVER.

52,220.

Specification for Design.

Patented July 23, 1918.

Application filed January 19, 1918. Serial No. 212,845. Term of patent 14 years.

To all whom it may concern:

Be it known that I, LOUIS JACOT, a citizen of the Republic of Switzerland, residing at 5 York Terrace, Hockley Hill, in the city of Birmingham, England, having invented a new, original, and ornamental Design for a Wristlet-Watch Cover, of which the following is a specification, reference being had to the accompanying drawing, forming part thereof.

Figure 1 is a front elevation, and Fig. 2 an end elevation of a wristlet watch cover made in accordance with this design.

I claim:

The ornamental design for a wristlet watch cover as shown.

LOUIS JACOT.

Witnesses:

FRANCIS MALPAS,
DORIS MILLWARD.
